UNITED STATES PATENT OFFICE.

ARTHUR J. SAALFIELD, OF BROOKLYN, NEW YORK.

DESIGN FOR A BOOK-COVER.

SPECIFICATION forming part of Design No. 25,704, dated June 30, 1896.

Application filed May 28, 1896. Serial No. 593,520. Term of patent 3½ years.

To all whom it may concern:

Be it known that I, ARTHUR J. SAALFIELD, a citizen of the United States, residing at Brooklyn, in the county of Kings and State of New York, have invented and produced a new and original Design for a Book-Cover, of which the following is a specification.

My design is illustrated in the accompanying drawing, which shows a face view of a book-cover ornamented according to my invention.

In the drawing the letters A B designate two tapering bars, the small lower ends of which extend through the curled ends of a streamer C, while their upper ends are connected by a garland D, the ends of which

are loosely twisted around the bars A B. The space inclosed by the streamer C, bars A B, and garland D is ornamented by two oval rings E F, the ring E inclosing the ring F. ²⁰

What I claim as new, and desire to secure by Letters Patent, is—

The design for a book-cover as herein shown and described.

In testimony whereof I have hereunto set ²⁵ my hand in the presence of two subscribing witnesses.

ARTHUR J. SAALFIELD.
